DEVICE FOR TESTING GAS LINES

Irwin M. Marx, University Heights, Ohio

Application September 21, 1954, Serial No. 32,381

Term of patent 14 years

(Cl. D52—1)

FIG. 1

FIG. 2

Fig. 1 is a front elevational view of a device for testing gas lines, showing my new design.

Fig. 2 is a side elevational view of the device for testing gas lines.

I claim:

The ornamental design for a device for testing gas lines, substantially as shown.
